UNITED STATES PATENT OFFICE.

JOSEPH CORBIERE, OF NEW YORK, N. Y., ASSIGNOR TO NICK GOVIN, OF NEW YORK, N. Y.

FUEL ECONOMIZER.

Application filed September 18, 1926. Serial No. 136,293.

The present invention relates generally to fuel economizers, but more particularly has to do with means for humidifying or moistening the hydrocarbon explosive mixture of an internal-combustion engine subsequent to carburization.

The main purpose of the invention is the production of a water-jacketed muffler wherein the heat radiated from the exhaust 10 gases from the engine is utilized to generate steam for transmittal to the intake manifold by means of the suction induced by the pistons of the engine.

Another object is to provide a water-circulatory system wherein the water may be pre-heated before admission to the main heating chamber.

A further object resides in the provision of valved-means for regulating the flow of 20 water into the heating chamber in proportion to the steam generated therefrom.

The invention is further featured by the production of a combined heater and muffler wherein the novel and unique assembling of 25 parts increase the workability and efficiency of the functioning of the device as a muffler and further utilize the waste heat radiated by the exhaust gases therein.

With these objects in view, together with 30 others which will appear as the description proceeds, the invention resides in the novel formation, combination, and arrangement of parts, all as will be described more fully hereinafter, illustrated in the drawings, and 35 particularly pointed out in the claims.

In said drawings:

Figure 1 is a central longitudinal sectional view of an economizer, constructed in accordance with my invention.

40 Fig. 2 is a transverse section taken substantially on the line 2-2 of Fig. 1.

Fig. 3 is a transverse sectional view taken on the line 3-3 of Fig. 1.

Fig. 4 is a representation of a typical internal combustion engine illustrating the connection effected therewith and my device.

Fig. 5 is a detail of a spider-member; and

Fig. 6 is an edge view thereof.

Those skilled in the art to which this invention appertains will at once recognize the component parts of my device in view of its similarity to the well-known form of muffler, and as clearly shown in Fig. 1, the casing 5 is closed at both ends by heads 6 and 7, each having a centrally apertured hub portion 8 and 9, the former receiving

the discharge end of the pipe 10, while the latter serves as a port for the exit of the spent gases.

Said pipe 10 is connected to the exhaust 60 pipe 11 from an internal combustion engine A, (see Fig. 4), through the medium of the coupling 12, the exhaust gases from said engine emerging from a plurality of apertures 13 in said pipe, and an aperture 14 arranged centrally in a cap 15, screwed to the inner end thereof.

The steam-generating portion of my device comprises a casting 16, which has been uniquely designed to define a chamber 17, 70 to contain a suitable quantity of water, and a heating chamber 18 into which latter extends the exhaust end of said pipe 10, as aforesaid. By coring out this casting circularly to the point adjacent its forward end 19 and boring centrally I develop the extension 20 which interiorly defines the said heating chamber 18 and said chamber 17 which surrounds the former for an appreciable distance. Said casting 16 is rigidly supported within the casing 5 through the intermediary of spiders 21 and 22, each having a central aperture 23 to receive said casting and radial ears 24, suitably fastened to said casing as indicated at 25. In order to prevent longitudinal displacement of the casting I prefer to interpose the sleeve members 26 between the forward end thereof and the head 6 and fasten same by screws 27 and in order to effect a tight connection between the casting and the pipe 10 a plug 28 is introduced.

Obviously such a construction results in a sturdy and firm structure well adapted to withstand the jolts attending the operation 95 of a motor vehicle. The provision of the ears 24 of the spiders 21 and 22 permits the free passage of the exhaust gases emerging from the chamber 18 by means of a plurality of radial ports and thence along the inner periphery of the casing and escaping through the aperture in the hub 9, all of which as will be clearly understood upon inspection of Figs. 2 and 3.

The water-supply pipe 30 may enter 105 through the head 7 and extend longitudinally of the casing to the forward end 19, whereupon it rises vertically and continues along the top of the casting and finally enters the chamber or reservoir 17, through the head 31 of the casting. The ears of the spiders 21 and 22 are apertured, as at 32 to

serve as a support of said pipe and maintain the same in close proximity to said casting for the obvious purpose of subjecting its fluid content to the preheating action of the exhaust gases. Means to regulate the flow of the water through the pipe is provided in the form of a float valve 33, its function and purpose being so well-known further description seems hardly necessary.

10 The generated steam from the device is transmitted to the intake manifold 34 of an internal combustion engine A, by means of the pipe 35, suitably valved, as indicated at 36.

15 From the foregoing it is apparent I have designed a device wherein the exhaust gases from the exhaust manifold 37 pass to the pipe 10 which emerge from the apertures in said pipe, the heat thereof coming in contact

20 with the wall 20 and turning the surrounding water into steam. The continued passage or baffling of the hot exhaust gases through the ports 29 along the inner periphery of the casing is utilized to further heat

25 the water and to appreciably raise the temperature of the water in the water supply pipe 30.

By my construction practically all available heat units in the gas is used and the 30 result is a dry superheated steam, admirably adapted to conveyance to the intake manifold for union with the explosive mixture, which latter is further vaporized and split-up to an appreciable degree.

35 In the event the device is used in connection with water-craft the water from the stream may be drawn into the device, but in the case of a motor-vehicle I propose to use tanks of standard construction and posi-

tion same either in conjunction with the 40 ordinary gas tank or as a separate unit.

I claim:

1. In an internal combustion engine, a water-jacketed muffler adapted for connection with the end of an exhaust pipe, said 45 muffler comprising a casting having a central bore terminating short of the end thereof, and a cored portion defining a water-receiving chamber concentric with said bore and a housing concentric with said casting 50 and spaced therefrom to define a space therearound, said casting being apertured to define exit means for the gases from said pipe to said space and means for supplying water to said chamber, said means being arranged 55 within the housing to subject its contents to the preheating action of the exhaust gases.

2. In an internal combustion engine, a water-jacketed muffler adapted for connection with the end of an exhaust pipe, said 60 muffler comprising a casting having a central bore terminating short of the end thereof to receive said pipe, said casting being cored longitudinally and concentric with said bore to define a water-receiving chamber 65 extending substantially to the inner end of said casting, a housing positioned over said casting and spaced therefrom to define a space therearound, said casting having exit means in the inner end thereof to permit the 70 escape of the gases from the bore to the space around said casting and means for supplying water to said chamber, said means being arranged within the housing to subject its contents to the preheating action of the 75 exhaust gases.

In testimony whereof I affix my signature.
JOSEPH CORBIERE.
